ANDREW DOWNER, OF HAMMONDSVILLE, OHIO.

Letters Patent No. 102,513, dated May 3, 1870.

IMPROVEMENT IN PRUNING-HOOKS.

The Schedule referred to in these Letters Patent and making part of the same.

To all whom it may concern:

Be it known that I, ANDREW DOWNER, of Hammondsville, in the county of Jefferson and State of Ohio, have invented a new and useful Improvement in Pruning-Hooks; and I do hereby declare that the following is a full, clear, and exact description thereof, which will enable others skilled in the art to make and use the same, reference being had to the accompanying drawing forming part of this specification.

The object of this invention is to provide an efficient instrument for pruning trees, hedges, vines, or briars; and

It consists in a pruning-hook, and in a saw combined therewith, arranged to operate as hereinafter more fully described.

In the accompanying drawing—

Figure 1 is a side view of the pruning-hook, shown without the saw.

Figure 2 is a section of fig. 1, one the line *xx*.

Figure 3 is a side view of the article, showing the saw attached.

Similar letters of reference indicate corresponding parts.

A is the staff, which is made of wood, and of any desired size and length.

B is a cutter, with sharp cutting-edge *C*, the shank of which is made fast in the staff.

D is the hook, which is connected with the cutter by clips *E* *F*, and made to slide thereon by means of the rod *G*, one end of which rod is removably attached to a lug, *H*, on the clip *E*, and the other end to the lever *I*. This lever has its fulcrum at *J*, on a plate, *K*, attached to the staff.

The operation of cutting twigs, limbs, and briars will be readily understood from the drawing.

In cutting, the lever is depressed, which forces the twig or limb down onto the edge *C* of the cutter *B*.

The form of the cutter and of the hook is such that the twig or limb is sheared off between them, and the purchase obtained by means of the lever allows a force to be applied sufficient for ordinary pruning.

L is a saw, which is combined with the hook, as seen in fig. 3. An edge view of the saw is seen in fig. 2, in dotted lines. It has a mortise, which slips over the lug *H*, and a pin near its lower end, which enters a hole, *m*, in the cutter *B*. When the saw is thus placed, the rod is adjusted, as seen in fig. 3, a small key is passed through a hole in the lug, and the connection is complete.

For cutting limbs which cannot be readily severed with the cutter, the saw is very convenient. It is readily adjusted and detached, and the manner in which it is connected with the hook renders it most efficient in the process of pruning.

Having thus described my invention,
I claim as new and desire to secure by Letters Patent—

The combination of the cutter *B*, hook *D*, and saw *L*, when the latter is connected with the former, substantially as and for the purposes shown and described.

ANDREW DOWNER.
